UNITED STATES PATENT OFFICE.

EDWIN P. CARPENTER AND MORRIS S. WRIGHT, OF FOXCROFT, MAINE,
ASSIGNORS TO ALICE P. CARPENTER, OF SAME PLACE.

ORGAN-ACTION.

SPECIFICATION forming part of Letters Patent No. 326,624, dated September 22, 1885.

Application filed March 6, 1884. (No model.)

To all whom it may concern:

Be it known that we, EDWIN P. CARPENTER and MORRIS S. WRIGHT, both citizens of the United States, and residing at Foxcroft, in the county of Piscataquis and State of Maine, have 5 invented certain new and useful Improvements in Organ-Actions; and we declare the following to be a description of our said invention sufficiently full, clear, and exact to enable others skilled in the art to which it appertains to make and use the same, reference being had to the accompanying drawings, which form a part of this specification.

Our present invention relates to certain improvements in construction, arrangement, and operation of various parts of the action, as hereinafter fully explained, with a view to the production of a convenient, efficient, and more desirable instrument, and to afford an action mechanism that can be manufactured with practical economy and dispatch.

The particular features of invention claimed are hereinafter definitely specified.

In the drawings, Figure 1 represents an end view of our improved organ-action. Fig. 2 is a transverse vertical section showing the relative arrangement of the stops, connections, and operating parts of the action. Fig. 3 is a plan and section detail showing the arrangement of the crank-levers in connection with the fulcrum-bar. Fig. 4 is a transverse vertical section of the action, showing the grand-expression connections in open position, and also illustrating the construction of the depressing devices used in cases where it is desired to operate a single crank-lever by two separate movements or by two separate pulls. Fig. 5 is a longitudinal section through the sound-board, showing the back of the action and crank-lever mechanism drawn to smaller scale; Fig. 6, a back view of the reed-board and mutes longitudinally, showing the arrangement of the auxiliary reeds, which operate only with the grand-expression devices. Fig. 7 is a vertical section through the detachable connecting device by which the crank-levers are joined to the mute-actuating wires, drawn to larger scale. Fig. 8 is a back view of the same. Fig. 9 is a front view of the 50 crank-lever head and section of the mute-connection

wire. Fig. 10 is an end view of the crank-lever end.

In the construction of our present organ-action the sounding-board S, tube-block T, playing-valves V, pitman-pins v, manual-keys W, and key-supporting frame w are all constructed and arranged substantially in the ordinary manner, and therefore need not be herein more particularly described.

A designates the name-board or brace, in which the stop pull-bars P are supported in the manner indicated.

B denotes a fulcrum-bar on which the wire crank-levers C have support. Said bar B extends across the instrument beneath the rear portion A' of the brace, and back of the manual-keys. Its ends are connected with supporting-pieces B', that rest upon the top of the key-frame, and which in turn form a support for the brace A in the manner illustrated, the several cheeks or ends being flush with each other on the outer side.

The key-frame, the fulcrum-bar devices, and the brace mechanism are each made up as separate parts, and the three are detachably connected together by means of the double hooks or swinging lock-bars D, at the ends of the action. Said lock-bars are pivoted at b on the fulcrum-bar cheeks B', and their ends hook onto studs d and d', respectively fixed in the ends of the key-frame and brace-piece, as illustrated in Fig. 1. By swinging back the bars D the brace A, with the pulls P, can be removed from the action; then by pressing back the hooks b', at the front part of the ends B', the fulcrum-bar B and parts connected therewith can be readily removed. This feature of making the brace and pull mechanism separate and detachable from the fulcrum-bar and its connections, and the latter separable and readily detachable from the other portions of the action, is of our invention, and is of considerable practical utility and convenience in the manufacture of the actions, and the facility of putting them into their cases, as well as for convenience for repairs. The crank-levers C are made of wire bent in the form indicated, with arms that extend upward and forward, having ends e, turned at an angle beneath the pulls P, to be acted upon by the depressing 95 100

devices F, and with downward-extended arms c', provided with wooden end pieces or heads c³, that are connected by the wire links m with the mutes M and other parts to be operated by the stop-pulls P. The fulcrum-bar B is made with a single longitudinal groove, b⁴, in its upper side, into which the horizontal parts c² of the crank-levers C are laid, with suitable felt packings placed beneath them to form 10 bearings, and packings of leather are then placed over these bearings, and staples b³ are driven into the bar in the manner indicated in Fig. 3, which serve to confine the parts in position, while permitting free working action, 15 thus forming a very complete and desirable fulcrum-bearing for the crank-rod C. The series of levers C extend downward at intervals along the back of the fulcrum-bar B, which latter is provided with vertical recesses b⁵, for 20 permitting their free action, and the rods m connect from said crank-levers to the mutes M direct; or, in the case of the rearward-opening mutes, the direction of motion is changed by rocker-levers m', interposed in the manner indicated. The mutes are hinged to the tube-board for opening and closing in the ordinary manner.

The crank-levers C and mute-actuating wires are connected to each other by a detachable adjustable joint device consisting of parts formed and arranged as shown in Figs. 7, 8, 9, and 10. A head-block, C³, of wood, is fixed on the wire lever C'. Said block has a conical recess, e', through it, and a slit, e², extending from its end into the recess. The wire m is screw-threaded at its end, and a turned wood button, E, having an extended shank, e, is screwed onto the end of said wire, which head engages block C³ in the manner shown. The opening e' is of sufficient size to freely receive the shank e of the button E, and the slit e² is wide enough to allow the passage of the wire m, but not the shank e. Disengagement of the connection 45 may be effected by drawing back the rod m till the shank is free from the block, and then dropping the wire m through the slit e². A packing of felt, e⁴, is placed on the head C³ beneath the button.

50 By making the head C³ of wood, in the form shown, and providing a wood button, E, screw-threaded directly to the wire m, a very simple, convenient, and desirable connection is produced, which permits adjustment and 55 detachment of the parts as desired.

The arrangement of the levers C and fulcrum-bar B, and the manner of constructing the connecting joint, as herein shown, are features of our invention. The parts c of the 60 lever on which the pull device acts is arranged transversely to the direction of the movement of the pull-bar P, and, in the case of the single-movement levers, a tumbler or depressing piece, F, (see Fig. 2,) is pivoted 65 in the pull-bar, with its opposite end resting across the part c of the crank-lever, in a manner to effect the depression of said lever and

the operation of the mute when the stop is pulled. In the case of such stops as are to have two movements, one for partially and 70 the other for completely raising the mute, we employ stop-bars having inclined lugs F' F², as shown in Fig. 4. The lug F' on one of the pulls depresses the lever C for a greater distance than does the lug F² on the other pull-bar. The part c of the crank-lever in this 75 case extends laterally across from one pull to the other, so as to receive the action from both of the pull-bars. The part c of the lever may be provided with a roll to take the bearing of the lug F'. The depressing-lugs can be made adjustable, as indicated in Fig. 4, by means of the screws f and f', one of which connects the lug to the pull-bar, while the other serves as a set-screw for pressing outward the heel of the lug. In this case the lug and bar are fitted together with a tongue and groove, so that the lug cannot swing around 80 out of line with the pull-bar.

G indicates the expression-roller or grand-swell actuating bar. It is hinged to the under side of the fulcrum-bar B in a position forward of the depending ends of the crank-lever C and extending the full length of the instrument. Said expression-roller G is connected for action 9; with an ordinary knee-swell or pedal (not shown) by the arm G', link g, and cranked rocking bar G², and it is operated by a backward movement (see position in Fig. 4) for bringing into action the entire power and tone 100 of the instrument. Along the lower edge of the roll or bar G is a series of adjustable buttons, I, that strike against and press back the respective levers C for opening the mutes M when the said expression-roll is operated. 105

H indicates the swell-board, and K and K' indicate the swells at the front and rear of the tube-block. The mute-connections are located beneath the swell-board H, so that the necessity for numerous openings through said board 110 are avoided and a closer and better swell-chamber is secured. The swells K and K' are hinged or pivoted centrally of their width, so as to open at both the upper and lower edges, as indicated by dotted lines, Fig. 2. 115 The swell is made with a pivot-stud at one end, and with a cranked bearing or pivot, k, at the other. This bearing k is laid into a depression, j, in the edge of the cheek-frame, and is there secured by a button, h, which turns 120 down over the bearing and secures it in place. The spring J for closing the swell consists of a wire which has its end fixed in the wood of the swell, and which extends along parallel 125 to the exterior of the end or cheek piece, where its extremity is turned at a right angle, and a torsional strain is put onto the wire by passing this end above a stud, i, set in the outside of the cheek-piece, as shown. The advantage 130 of this construction of the swell devices is that by simply swinging up the button h the spring and bearing of the swell are freed, and the swell can then be readily taken out to permit

access to the reed-blocks and reeds, and as readily replaced, since it is only necessary to raise the bearings or pivots from the recess to free the swell, there being no permanent connections along its edges. The swells K and K' are provided with rolls l on the outer end of their cranked pivot-bearings, which are engaged by the lifting-bar L, which latter is actuated by means of the ordinary knee-pad (not shown) for opening the swells as required. The swell K is also connected for operation to one of the levers C of the stop-pull mechanism, as indicated at K³, Figs. 4 and 5, so that it can be raised by drawing the stop, or in connection with the grand-expression roller G when the latter is operated. Combined with the action we employ a partial set of reeds, N, the tones of which are ranged between the "violoncello" and "sub-base" sets, and which are arranged to be brought into action by the grand-expression mechanism only. The arrangement of the devices for bringing into action this partial set of reeds in the present instance is shown in Figs. 4, 5, and 6. The mute M' is connected by wire m² to an angle-lever, N', which is in turn joined by the wire m³ to an arm, n, fixed on the expression-roller G, so that when said roller G is pressed back (see Fig. 4) the mute M' will be raised and the reeds N permitted to speak as the manual-keys are depressed, but at all other times except when the grand expression is operated the reeds N are closed in and remain silent, the partial set of reeds being brought into action with the grand expression only. A feature of our invention is the arrangement of the devices for effecting this result.

O indicates the sub-base action, which may be of ordinary construction. Its mute M² is connected by the wires m⁴ to a change-lever, which in turn is connected to one of the crank-levers C to be operated by a stop-pull, as indicated.

R and R' designate the connections for working the swell and bellows-indicator mechanism, which is located at the central part of the name-board A. This indicator mechanism is not a part of our present invention.

Y indicates the pitman-pin for opening the valve Y' of the tremolo mechanism, which is arranged in the manner illustrated in Fig. 1. The rod Y is depressed by an inclined lug, F³, on one of the stop-pulls P when said stop is drawn for bringing the tremolo into operation.

What we claim as of our invention, and desire to secure by Letters Patent, is--

1. The construction and arrangement of organ-action mechanism, as described, viz.: with the brace-section A, the fulcrum-bar section B B', and the key-frame section w as separate detachable parts, with connecting devices, as hooks D, which permit of their ready removal one part from the other, substantially as and for the purpose set forth.

2. The combination, with the sounding devices and key-frame in an organ-action, of the detachable fulcrum-bar B, carrying the crank-levers and grand-expression roller, the detachable brace A, carrying the pull-bars, and the connecting-hooks D, pivoted to the fulcrum-bar ends, as at b, and adapted to engage studs d d', respectively fixed on the ends of said brace and key-frame, for detachably retaining said parts in position, substantially as set forth. 65

3. The crank-lever C, provided with the wood end block c³, fitted with conical recess c' and end slit, e², in combination with the mute-actuating wire m, screw-threaded at the end and provided with the wooden button E, screwed directly upon said wire and having the shank e extending through the recess e² of said lever end block, as set forth. 75

4. The combination of the fulcrum-bar B, the cranked levers C, expression-roller G, and the adjusting screw-buttons I, substantially as shown and described, for the purposes specified. 85

5. The combination of the pull P, provided with the depressing-piece F, the wire crank-lever C, supported in the grooved fulcrum-bar B and having the offset top end, c, and dependent arm c', with joint-block c³, the mute-actuating wire m, and the expression-roller G, having adjustable studs I, substantially as and for the purpose set forth. 90

6. The combination, with the pull-bar P and wire crank-lever C, of the inclined actuating-lug F², connected to said pull in the manner shown, with the attaching-screw f and adjusting-screw f', for the purpose set forth. 95

7. The combination, with the reed-board S, tube-block T, and swell-board H, in a reed-organ action, of the centrally-pivoted swells K K', having their bearing-pivot h and closing-spring J, secured in a recess formed on the edge of the cheek-piece or end frame by the button h in the manner described, whereby ready detachment of the swell can be effected, substantially as and for the purpose set forth. 105

8. In a reed-organ action, the combination, with the expression mechanism and tube-board, of the auxiliary reeds N, their mute M', and the link devices m² m³, angle-lever N', and arm n, connecting said mute with the expression-roller G for operation therewith substantially as and for the purpose set forth. 115

Witness our hands this 16th day of February, A. D. 1884.

EDWIN P. CARPENTER.
MORRIS S. WRIGHT.
